Primary Examiner — Jonathan J Han*Assistant Examiner* — Christen Pilar Brown(74) *Attorney, Agent, or Firm* — Greer, Burns & Crain, Ltd.(57) **CLAIM**

The ornamental design for a footwear upper and midsole, as shown and described.

DESCRIPTION

FIG. 1 is a front perspective view of a footwear upper and midsole showing my new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines on the sole and the interior of the footwear depict the bounds of the claim. The broken lines on the rear heel and the outsole form no part of the claimed design. The dashed seam edge lines shown on the footwear upper depict stitching, which does form a part of the claimed design.
